(57) **CLAIM**

I claim the ornamental design for a dispenser, as shown and described.

DESCRIPTION

FIG. 1 is a perspective view of a first embodiment of a dispenser showing my new design;
FIG. 2 is a front view of the dispenser in FIG. 1;
FIG. 3 is a right side view of the dispenser of FIG. 1;
FIG. 4 is a left side view of the dispenser of FIG. 1;
FIG. 5 is a top view of the dispenser of FIG. 1;
FIG. 6 is a bottom view of the dispenser of FIG. 1;
FIG. 7 is a back view of the dispenser of FIG. 1;
FIG. 8 is a perspective view of a second embodiment thereof; and,
FIG. 9 is a perspective view of a third embodiment thereof. The broken line showing in the figures is included for the purpose of illustrating portions of the dispenser and form no part of the claimed design.
